(57) **CLAIM**

The ornamental design for a water heater support, as shown and described.

DESCRIPTION

FIG. 1 is a perspective view of the water heater support. FIG. 2 is a front elevational view of the water heater support. FIG. 3 is a rear elevational view of the water heater support. FIG. 4 is a left side elevational view of the water heater support.

FIG. 5 is a right side elevational view of the water heater support.

FIG. 6 is a top plan view of the water heater support.

FIG. 7 is a bottom plan view of the water heater support; and,

FIG. 8 is a perspective view of the water heater support shown supporting and fixing the top of a water heater to a nearby wall structure.

The broken lines in FIGS. 1-7 show environmental structures of the water heater support and form no part of the claimed design. The broken lines in FIG. 8 shows the boundary of the view of the environment of use of the water heater support and environmental structures of the water heater support and form no part of the claimed design.

1 Claim, 7 Drawing Sheets
